UNITED STATES PATENT OFFICE.

BENJAMIN C. VANDUZEN OF WINTON PLACE, OHIO.

LUBRICATING APPARATUS FOR ENGINES

SPECIFICATION forming part of Letters Patent No. 636,014, dated October 31, 1899.

Original application filed September 13, 1894, Serial No. 522,898. Divided and application filed July 1, 1898, Serial No. 684,978. Again divided and this application filed December 29, 1898. Serial No. 700,615. (No model.)

To all whom it may concern:

Be it known that I, BENJAMIN C. VANDUZEN, a citizen of the United States, and a resident of the town of Winton Place, in the county of Hamilton and State of Ohio, have invented certain new and useful Improvements in Lubricating Apparatus for Engines, of which the following is a specification.

The invention herein set forth is a division
10 of one for which application was filed July 1,
1898, and bore the Serial No. 684,978, and the
said application, Serial No. 684,978, is a divi-
15 sion of an application, Serial No. 522,898, filed
September 13, 1894, and which after division
resulted in the Letters Patent No. 609,253,
dated August 16, 1898. Due reference is here-
by made to the said applications.

My apparatus is especially designed for an engine whose cylinder has a piston driven from one side only.

My apparatus although especially designed for engines driven by carbureted air or gas is applicable to other engines.

The several features of my invention and the various advantages resulting from their use conjointly or otherwise will be apparent from the following description and claims.

In the accompanying drawings, making a part of this application, similar letters of reference indicate corresponding parts.

Inasmuch as my invention is primarily applicable to engines driven by the explosion of carbureted air or gas, I have for the purposes of sufficient illustration shown my invention 35 as applicable to a common kind of such engines.

As my apparatus is confined to the pitman and its connections at one end with the cross-head, I have deemed it sufficient to show a cylinder, piston, cross-head, crank, and crank-shaft duly assembled and my apparatus duly applied thereto.

45 Of the drawings, Figure 1 shows a vertical section of the cylinder, the piston, the cross-head, the journal-box of the crank-wrist, and the journal-box of the crank-shaft, while the crank and its wrist and certain bolts, &c., as well as portions of the oiling apparatus, are shown in elevation. Fig. 2 represents an en-

50 shown in elevation. Fig. 2 represents an enlarged vertical central section of the plunger, receiving-tube, ball-valve, and stop, the latter being shown in elevation. Fig. 3 repre-

sents an enlarged cross-section of the plunger, taken at the dotted line 21-21 of Fig. 2, the plunger being surrounded by the receptacle 55 for the oil.

Q indicates the cylinder of the engine, Q^2 a jacket or outer shell, and Q^3 a space formed between the jacket and the cylinder.

Q^4 is the head of the cylinder, and Q^5 the space formed therein. The spaces or chambers Q^4 and Q^5 are common to receive water. The latter is changed as fast as desired, and the cylinder is thereby kept cool.

The cylinder Q is suitably supported. A preferred means consists of a foundation Q⁶, supported upon the reaches A². The foundation is preferably cast in one with the cylinder. The crank-shaft is also suitably supported. In the present instance the foundation Q⁶ forms the support for the crank-shaft. Through the center of this foundation is a horizontal opening or journal-bearing Q⁷, in which latter is present the crank-shaft turning therein. Between the reaches A³ the foundation is extended downward in a reefangon- 70 75

deration is extended downward in a rectangular extension Q^8 , substantially as shown, for the purposes of increasing the strength of the foundation. The cylinder is suitably united to the foundation, preferably by being cast in one therewith. Through the center of this foundation is a horizontal opening or journal-bearing Q^7 , in which latter is present the crank-shaft F , turning therein. The crank Q^9 is connected to the crank-shaft F substantially as shown and in the same manner as is the case in center-crank-shaft engines. The crank Q^9 is provided with a wrist-pin Q^{10} , in turn connected by a suitable box-journal Q^{12} to the lower end of a pitman or connecting-rod Q^{13} , whose upper end is connected, by means of the journal-box Q^{14} , to the cross-head or wrist Q^{15} , the latter being bolted, by means of stud-bolts Q^{16} , to the piston-head Q^{17} , the latter being provided with packing, preferably of a metallic kind well known in the arts. 95

Where the cylinder belongs to an engine of the kind which has a piston-rod, the cross-head will be duly secured to that end of the piston-rod which is opposite where the piston is attached. 100

I will now describe the device for lubricating the wrist Q¹⁵.

^{Q18} indicates the sight-feed or oil-reservoir.

connected to the delivery-pipe Q¹⁹, which in turn is connected to a vertical dip tube or vessel Q²⁰, whose upper end is located in the lower portion of the cylinder Q. A dipper 5 Q²¹, hollow within, has a central orifice Q²³, which orifice is enlarged above, forming the passage Q²⁴. A ball-valve Q²⁵ rests on the upper end of the narrow passage Q²³ and is allowed vertical play between the shoulders 10 Q²⁶ of the passage Q²⁴ and a stop Q²⁷, located across the passage Q²⁴. The passage Q²⁴ is continued up through the recess Q³² in the cross-head Q¹⁵ and passes to the upper surface of the cross-head and within the box Q¹⁴. The 15 operation of this part of the device is as follows:

As the piston descends the lower end of the dipper enters the dip-tube Q²⁰, filled with oil. The oil is forced up through the passage 20 Q²³ of the dipper and leaving the valve Q²⁵ passes around same and into the passage Q²⁴. As the piston rises the valve Q²⁵ descends and prevents the oil in passage Q²⁴ from returning through passage Q²³. Successive reciprocations of the piston increase the amount of oil 25 in passage Q²⁴ until it (the oil) soon reaches the upper side of the box Q¹⁴ and lubricates the wrist Q¹⁵ of the pitman or connecting-rod. Successive reciprocations of the piston-head 30 continue to steadily supply the required quantity of oil to the wrist Q¹⁵ and journal-bearings Q¹⁴ of the pitman or connecting-rod. The sight-feed or oil-reservoir Q¹⁸ has an adjustable screw in common use, whereby the quantity of oil delivered through the delivery-tube Q¹⁹ can be regulated so as to feed the requisite amount of oil, and no more, to the dip-tube Q²⁰. Attention is called to the fact that 35 the lower portion of the orifice Q²³ is conically enlarged downwardly, substantially as shown in Fig. 2. This shape is a valuable feature

of invention, inasmuch as it enables the dipper to pump up the oil, whereas it would not to any extent take it up otherwise, even though the ball-valve Q²⁵ be present. When 4 this orifice Q²³, tapered, as shown, is present, the dip-tube Q²⁰ can be relied upon to promptly, readily, and always take up the amount of oil that is fed to it by the sight-feed Q¹⁸. 5

What I claim as new and of my invention, and desire to secure by Letters Patent, is—

1. In a lubricating apparatus, the combination of a piston, a valved dip-tube rigidly connected to said piston, and an oil-cup into which 5 said tube is adapted to dip, substantially as described.

2. In a lubricating apparatus, the combination of a cylinder open at one end, an oil-cup in the open end thereof, a piston in said cylinder, and a dip-tube, provided with a ball-valve, rigidly fastened to said piston, substantially as described. 6

3. In a lubricating apparatus, the combination of a cylinder, an oil-cup near one end of 6 said cylinder, a piston, and a dip-tube rigidly attached to said piston, said tube being provided with an outwardly-flaring mouth, a ball-valve and a stop for said valve, substantially as described.

4. In a lubricating apparatus, the combination of a cylinder open at one end, an oil-cup located in said open end, an oil-reservoir, pipes connecting said cup and reservoir, a piston, and a dip-tube rigidly attached to said 7 piston, said tube being provided with a ball-valve and an outwardly-flaring mouth, substantially as described. 7

BENJAMIN C. VANDUZEN.

EDWARD S. LEAVITT,
K. SMITH.

Correction in Letters Patent No. 636,014.

It is hereby certified that Letters Patent No. 636,014, granted October 31, 1899, upon the application of Benjamin C. Vanduzen, for an improvement in "Lubricating Apparatus for Engines," was erroneously issued to the inventor said Vanduzen as owner of said invention; whereas the said Letters Patent should have been issued to *The Huber Manufacturing Company, of Marion, Ohio, a corporation of Ohio*, as assignee, by mesne assignments, of the entire interest in said invention, as shown by the record of assignments in this Office; and that the said Letters Patent should be read with this correction therein that the same may conform to the record of the case in the Patent Office.

Signed and sealed this 14th day of December, A. D., 1909.

[SEAL.]

C. C. BILLINGS,

Acting Commissioner of Patents.

It is hereby certified that Letters Patent No. 636,014, granted October 31, 1899, upon the application of Benjamin C. Vanduzen, for an improvement in "Lubricating Apparatus for Engines," was erroneously issued to the inventor said Vanduzen as owner of said invention; whereas the said Letters Patent should have been issued to *The Huber Manufacturing Company, of Marion, Ohio, a corporation of Ohio*, as assignee, by mesne assignments, of the entire interest in said invention, as shown by the record of assignments in this Office; and that the said Letters Patent should be read with this correction therein that the same may conform to the record of the case in the Patent Office.

Signed and sealed this 14th day of December, A. D., 1909.
